UNITED STATES PATENT OFFICE.

SAMUEL RUBEN, OF NEW YORK, N. Y.

VACUUM TUBE.

Application filed June 3, 1924. Serial No. 717,501.

This invention relates to a vacuum tube and therefore, its impedance and the plate current flow. 5
This invention relates to a vacuum tube and therefore, its impedance and the plate current flow. 10
This invention relates to a vacuum tube and therefore, its impedance and the plate current flow. 15
This invention relates to a vacuum tube and therefore, its impedance and the plate current flow. 20
This invention relates to a vacuum tube and therefore, its impedance and the plate current flow. 25
This invention relates to a vacuum tube and therefore, its impedance and the plate current flow. 30
This invention relates to a vacuum tube and therefore, its impedance and the plate current flow. 35
This invention relates to a vacuum tube and therefore, its impedance and the plate current flow. 40
This invention relates to a vacuum tube and therefore, its impedance and the plate current flow. 45
This invention relates to a vacuum tube and therefore, its impedance and the plate current flow. 50

An object of the invention is to attain certain new and important advantages in tube operation, as by always utilizing the full value of the electron stream discharge to the anode. 55

There are two commonly known types of electron discharge tubes, one of which comprises a heated cathode and an anode or plate element, having interposed therebetween a control element connected to a source of variable potential to control or modulate the electron stream between the cooperating electrodes by blocking or obstructing its path to a degree depending upon the magnitude or sign of the potential, causing variations in the plate current. The other type of tube also has the cathode, anode and plate elements, but the control element is not

interposed between the cathode and anode, and the electron stream is controlled by a transverse electrical field established by the potential impressed upon the controlling element, which serves to deflect or otherwise alter the course of the stream from its normal path between the cathode and anode. In such a tube the controlling transverse field must be directly in the electrical field of the discharge between the cathode and anode. 60
The tube of my invention differs from those of the prior art in that its operation is based upon the employment of the potential applied to the control element to vary the repulsion between the electrons of the stream to control the effective plate area, 65

I have found that if the anode is so placed that its edge is parallel and closely adjacent to the cathode, the electron stream does not discharge chiefly to the edge, but is distributed over the adjoining plate surface, as well, the area of distribution varying in proportion to the space charge or the repulsion reaction between the electrons, as determined by the stream density, due to the electrostatic or magnetic fields. The control element is so placed that when it is negatively charged as to the anode the electron stream is constricted, causing an increase in the electron repulsion reaction and therefore, an increase in the density of the limiting space charge, a decrease in the stream flow and in the area of stream distribution, 70 or effective plate area, towards the cathode. These effects vary in degree according to the magnitude of the impressed potential, and the reverse effects occur if the applied potential is of the opposite polarity. The impedance of the tube is controlled in this way. The control element must not be within the path of the discharge, and a plurality of control and anode elements may be arranged about the cathode. 75

The effect of the transverse field so established is not to transversely change the direction of the flow of the stream, but to change the area over which the stream discharges, varying the anode impedance accordingly; whereas, in the prior art, in those tubes in which the control element is not located between the cooperating electrodes, the effect of change of potential of the control element is to divert the stream to a path 80 transverse of the normal line of travel. For the proper operation of this tube, the narrow surface or edge of the plate element must be arranged approximately parallel to and closely spaced from the cathode, so that the space charge effect, due to the electrostatic field of the dense electron stream at the edge of the plate causes the distribution of the electron discharge over the surface of the plate, and the electron stream must discharge from the full length of the cathode surface. The control element is mounted outside of the space separating the cathode and anode, and with its narrow surface or edge adjacent the cathode and parallel 85 thereto and also parallel and adjacent to the anode. 90

The tube of my invention differs from those of the prior art in that its operation is based upon the employment of the potential applied to the control element to vary the repulsion between the electrons of the stream to control the effective plate area, 95

A tube constructed upon this principle is applicable to the usual vacuum tube uses, such as the detection and amplification of radio and audio frequency oscillations, and 5 to the generation of sustained oscillations.

The underlying principles of the invention may be better understood from an explanation of a concrete apparatus embodying those principles, as illustrated in the accompanying drawings.

In the drawings referred to,

Figs. 1 and 2 show elevations of a tube, and Fig. 3 shows a plan of the deflector or control plate; Fig. 4 illustrates diagrammatically a receiving circuit with the device connected therein. Figs. 5, 6 and 7 show plan views of the elements of the tube, and illustrate the discharge characteristics under the control of different potentials of the deflector plate.

Referring more particularly to the drawings, 1 represents the glass container, and 2, 3 and 5 respectively the anode, control and cathode elements. The cathode with outlet terminals at 8 and 9 is supported by 4. The terminals for the anode and control elements are respectively 10 and 7. In Fig. 4 the usual elements in a receiving system are conventionally represented. Fig. 5 indicates the electron stream discharge when control element 3 is not charged. When that element is negatively charged with respect to anode element 2, the electron stream is constricted as shown in Fig. 6, while Fig. 7 shows the wide discharge distribution when the control element is positively charged.

When the device is operated with no charge upon the control element there is no transverse electrostatic field between the co-operating electrodes, and the electron stream between the cathode and the anode is distributed generally as indicated in Fig. 5, over the surface of anode 2, permitting a constant plate current flow. But when a potential is applied to control element 3 and anode 2, as by the impression of oscillations from the antenna, a transverse electrostatic field is established in the path of the electron stream; if negatively charged with respect to the anode, the electron stream is constricted as shown in Fig. 6 and the distribution of the stream along the anode surface is reduced in a degree depending upon the magnitude of the potential difference between the two elements, the density of the field increasing the electron repulsion reaction, and thereby decreasing the effective plate area, and decreasing the plate current.

If the control element is positively charged with respect to the anode the repulsion reaction decreases, and there is a wider distribution of the electron stream, a lower plate impedance and an increased plate current flow. When employed in a detector circuit, as shown in Fig. 4, with a grid condenser, there is a unilateral effect of grid charging, and an increased rectification due to a better asymmetrical variation of the electron stream.

What I claim is:

1. An electron discharge device comprising a container having mounted therewithin an electron emission element and in the plane of and edgewise to said element, a co-operating anode element consisting of a plurality of plates, and a control element located outside of the electron accelerating field.

2. An electron discharge device comprising a container having mounted therewithin an electron emission element, and in the plane of and edgewise to said element, a co-operating anode element comprising a plurality of plates, and a control element.

3. An electron discharge device comprising an evacuated envelope containing an electron emitting element and a co-operating anode comprising a plurality of plates in the plane of and edgewise to said electron emitting electrode, and means for varying the area of impact of the electron stream upon the surface of the anode, comprising a control element having a plurality of plates adjacent to and parallel with said anode plates.

4. An electron discharge device having therewithin an anode composed of plates, an electron emission filament mounted between and parallel with edges of the plates of said anode, and a control element having plates equidistant from and parallel with a plane of the anode.

5. An electron discharge device having a filament cathode and a co-operating anode having two plates, said filament and plates being all in a common plane, and a control element having plates equidistant from and parallel with a plate of the anode.

6. An electron discharge device having a filament cathode, a co-operating anode comprising a pair of plates upon opposite sides of and in a plane with the filament, and a control element having a pair of plates parallel with each plate of the anode.

Signed at New York city in the county of New York and State of New York this 2nd day of June, A. D. 1924.

SAMUEL RUBEN.
